United States Patent Office

Des. 211,282
Patented June 4, 1968

211,282

UPRIGHT SUCTION CLEANER

Harold W. Schaefer and Samuel E. Hohulin, Bloomington, Ill., assignors to National Union Electric Corporation, Stamford, Conn., a corporation of Delaware

Filed Nov. 1, 1967, Ser. No. 9,231

Term of patent 14 years

(Cl. D49—14)

FIG. 1.

FIG.3.

FIG.4.

FIG. 5.

FIG. 6.

FIG. 1 is a perspective view of a suction cleaner illustrating our new design;

FIG. 2 is a side elevational view of the suction cleaner shown in FIG. 1;

FIG. 3 is a front elevational view of the suction cleaner of FIG. 1;

FIG. 4 is a top plan view of the suction cleaner of FIG. 1;

FIG. 5 is a rear elevational view of the suction cleaner of FIG. 1; and

FIG. 6 is a bottom plan view of the suction cleaner of FIG. 1.

We claim:

The ornamental design for an upright suction cleaner, substantially as shown and described.
